UNITED STATES PATENT OFFICE.

WILLIAM C. STRIPE, OF PITTSBURGH, PENNSYLVANIA.

AUTOMATIC STOKER.

Application filed February 25, 1922. Serial No. 539,109.

To all whom it may concern:

Be it known that I, WILLIAM C. STRIPE, a citizen of the United States, and a resident of Pittsburgh, county of Allegheny, and State of Pennsylvania, have invented certain new and useful Improvements in Automatic Stokers, of which the following is a specification, reference being had to the accompanying drawing.

10 My invention relates more particularly to that class of automatic stokers in which coal is fed from a hopper into the path of a reciprocating ram and forced by the latter through a throat into the fire box of the furnace. In the operation of devices of this character the forward or feeding movement of the ram is sometimes interrupted by the lodging of a hard lump of coal or some foreign body such as a piece of iron, stone 20 or the like, between the forward end of the ram and the throat of the fire box; it has therefore been customary in the art to provide means intended to prevent damage to the stoking mechanism under these circumstances which might otherwise occur by reason of the continuous application of power without a corresponding movement of the ram being possible; for example a frangible pin or shearing member employed to 25 operatively connect suitable parts of the mechanism which serves to actuate the ram; and adapted, in case the movement of the ram be obstructed, to break or shear and thus disconnect the ram from its actuating mechanism.

It has been found, however, that if the pin be made of sufficient strength to transmit the drive to the ram at certain points in its path of movement, it will not shear if the movement of the ram be interrupted at other points and more particularly when it nears the end of the feed stroke and the connecting rod and crank of the actuating means are approaching alignment, so that under these conditions a dangerous strain may be placed on the actuating mechanism; on the other hand, if the pin be made light enough to shear under such conditions it will frequently be unable to support the strain imposed on it in the normal operation of the mechanism especially when the crank and connecting rod are in a position of considerable respective angularity.

The principal object of my invention is 55 the provision of means in an automatic stoker of the general character aforesaid

which are effective upon the movement of the ram being interrupted from any cause, such as the lodgment of a foreign body between the ram and the fire box throat to 60 positively relieve the ram actuating mechanism from undue strain irrespective of the position of the ram.

A further object of the invention is the provision of means in an automatic stoker 65 adapted, when the movement of the ram is interrupted toward the forward end of the feed stroke, to permit the crank and connecting rod of the actuating mechanism to pass over the dead center while the ram remains stationary without shearing or rupturing any portion of the actuating mechanism or bringing an undue strain on any of the parts thereof.

My invention further comprehends the 75 employment in combination in an automatic stoker of a frangible pin or member adapted to shear if the movement of the ram be interrupted while the latter is at certain portions of its stroke and of resilient means 80 adapted to yield when the movement of the ram is interrupted at other portions of its stroke whereby, irrespective of the point at which the ram is blocked, the actuating mechanism is relieved from undue strain and 85 the shearing of the pin under certain conditions of operation avoided.

The invention further includes all of the other various objects and novel features of construction and arrangement hereinafter 90 more particularly specified or described.

For the purpose of enabling those skilled in the art to readily comprehend and practise the invention, I have somewhat diagrammatically illustrated in the accompanying drawing and will now proceed to describe a typical form of automatic stoker embodying my invention, Fig. 1 being a side view partially in elevation and partially in vertical section of the stoker and a portion 95 of the adjacent furnace, Fig. 2 a similar view with several of the parts in a different position, while Fig. 3 is a fragmentary rear end elevation of the ram and portions of the adjacent mechanism. Like numerals are used 100 to designate similar parts in the several figures.

As illustrated, the mechanism comprises a fuel hopper 1 communicating through a throat or fuel passage 2 with a fire box 3, 110 a horizontally reciprocating ram 4 being arranged in front of the throat to travel in a

suitable sleeve or casing 5, these parts being of any suitable construction. Means are provided for actuating the ram comprising a crank 7 of suitable throw conveniently 5 integral with a crank shaft 8 rotatably journaled in suitable standards 9, 9, the crank being connected with the ram through the medium of a two-part connecting rod 10 comprising relatively movable conveniently 10 telescopic parts 11 and 12, hereinafter more fully described, and adapted to oscillate on a wrist pin 13 carried by the ram.

For rotating the crank shaft 8 suitable means are provided, conveniently comprising 15 a worm gear wheel 15 carried by and normally rotative with the shaft and arranged to mesh with a worm 16 on a transversely extending worm shaft 17 journaled in suitable supports. Rotatable with this 20 shaft and secured thereto is another worm wheel 19 arranged to mesh with a worm 20 on the main drive shaft 21 which is supported in suitable standards 22 and actuated in any convenient way; as shown 25 through a sprocket wheel 23 and chain 24 driven from any suitable source of power.

One of the portions of the two-part connecting rod 10, conveniently the portion 12 which engages the wrist pin 13, is provided 30 with a preferably cylindrical longitudinal recess 26 into which the end of the other part 11 of the connecting rod is adapted to form a good working fit thus enabling relative longitudinal movement to take place between the two parts of the rod. Means are 35 provided for maintaining the parts of the rod in assembled relation which may also serve to limit the relative movement therebetween, said means being conveniently in 40 the form of a transversely extending pin 28 carried by the part 12 and extending through a suitable slot 29 in the part 11, engagement of the pin with the ends of the slot of course limiting possible relative longitudinal movement of the parts. Between 45 the end of the part 11 and the bottom of the recess 26 is positioned a relatively heavy coil spring 30 which is so adjusted as to normally maintain the part 11 as far away from 50 the wrist pin as it will go and as shown in Fig. 1, the function and operation of this spring being hereinafter more fully described.

Somewhere in the ram actuating mechanism and between the drive shaft 21 and the connecting rod, a suitable frangible pin or shearing element of other desired form is employed for holding certain of the parts in normally fixed relation, and while this pin 55 or element may be positioned at any suitable point I have shown the same in the form of a pin 32 which serves to hold the gear wheel 15 onto the crank shaft 8 by passing through the hub 33 of the wheel and through the 60 crank shaft as best shown in Fig. 3. The

strength of this pin is such that during the normal operation of the mechanism it is effective to maintain the gear wheel and crank shaft in fixed relation but in case under certain conditions hereinafter described, the movement of the ram is interrupted the pin will shear and allow the gear 70 15 to rotate freely on the shaft 8, thus permitting the latter with its connected parts to come to rest while the actuating mechanism for driving the gear wheel continues 75 in motion.

In the normal operation of the machine with the parts constructed and assembled substantially as hereinabove described, the ram is slowly reciprocated, the coal feeding down from the hopper during the retraction or back stroke of the ram to be pushed into the fire box upon the forward or feed stroke. If, however, the forward stroke of the ram 80 is arrested when it is well toward the outer end of its stroke as in Fig. 1 through the lodging of a large obstruction in front of the ram, the shearing pin 32 in consequence of the continued application of power from the drive shaft, will shear off and thus save the actuating mechanism from excessive strain. Under these conditions the spring 85 30 will normally remain extended or at most be only partially compressed prior to the shearing of the pin, as owing to the great angularity between the crank and the connecting rod the longitudinal thrust on the spring is relatively low while the shearing force exerted on the pin is relatively 90 great. On the other hand, in case the motion of the ram is arrested near the end of the feed stroke as by the lodging of a relatively small obstruction O between the ram and the edge of the throat, the continued 95 application of power to the actuating mechanism is effective to bring about a sufficient compression of the spring 30 to permit the crank and connecting rod to pass the dead center and retract the ram without shearing 100 the frangible pin, for under these conditions the longitudinal thrust on the connecting rod, due to the slight angularity between it and the crank, is very great in comparison with the force which tends to shear the pin 105 32. Of course upon the retraction of the ram the obstruction O is free to fall to a 110 position in which it will be forced into the fire box during the ensuing feed stroke.

It will thus be apparent that when the 115 movement of the ram is blocked by a relatively small obstruction so that the longitudinal pressure on the spring is relatively great, the spring will be sufficiently compressed to permit the crank and connecting rod to pass the dead center without excessive strain on the actuating mechanism and without in any way interrupting the normal operation of the machine, while when the ram is blocked at such point in its stroke 120 125 130

that the force tending to shear the pin is relatively great, the pin will shear to relieve the actuating mechanism from excessive strain, in which case of course it becomes necessary 5 to replace the pin before the ram can again be put into operation.

As in the practical operation of automatic stokers it is found that the jamming of the ram is in the great majority of cases 10 due to the presence of small foreign bodies in the coal as distinguished from bodies of relatively great size, it will be evident that a stoker embodying my invention may be kept in operation for a much greater proportion 15 of the time than a stoker in which a frangible pin or other element must be replaced every time that the movement of the ram is blocked by any sort of obstruction, large or small, as with my improved construction the replacement of the frangible pin is only required in the relatively rare instances in which the stoppage of the ram occurs when there is considerable relative angularity between the crank and connecting rod, or in other words, when it is brought about by a relatively large obstruction.

For the purpose of enabling those skilled in the art to comprehend and practise the invention, I have herein described and illustrated with considerable particularity a preferred embodiment of means suitable for attaining the objects thereof in connection with the stoker having but a single ram, but it will of course be understood that stokers of this general class are ordinarily arranged in batteries each battery having a plurality of rams feeding a corresponding number of retorts and actuated from the same crank shaft and my invention is particularly suitable for use in such installations since the shearing of the frangible pin in the ordinary type of stoker under such conditions results in putting not only a single ram but the whole battery temporarily out of commission. Furthermore, I do not desire or intend by the foregoing description and accompanying drawing to in any manner limit myself to specific details of construction or arrangement of parts or to any definite position of the frangible pin or other shearing element in the actuating mechanism, as the same may be placed therein at any suitable point, and the precise form and arrangement of the various elements varied from those shown without departing from the spirit and scope of the invention as defined in the appended claims.

Having thus described my invention, I claim and desire to protect my Letters Patent of the United States:

1. In an automatic stoker, the combination of a reciprocating ram, means for feeding fuel in front of the ram, actuating mechanism for reciprocating the ram com-

prising a two-part connecting rod, a frangible member operative to normally connect parts of said actuating mechanism to transmit power to the rod, and yielding means so associated with said connecting rod as to normally maintain the parts thereof in one position and operative in case the movement of the ram be arrested at certain points in its travel to permit relative movement of the parts of said rod to relieve the actuating mechanism of excessive strain.

2. In an automatic stoker, the combination of a ram, means to reciprocate said ram comprising a connecting rod formed with two sections, yielding means for normally maintaining said sections in one position, a crank and a train of gearing connected with said rod, and a frangible element adapted to normally maintain elements of said train in position to transmit power therethrough, said frangible element being operative to shear when the movement of said ram is arrested at certain points in its path and said yielding means being operative to yield when the movement of said ram is arrested at other points in its path.

3. In an automatic stoker, the combination of a ram, a two-part connecting rod connected therewith the sections of said rod being capable of relative longitudinal movement, a spring adapted to normally force said sections apart, a crank cooperative with said rod, a train of gearing adapted to rotate the crank, and a frangible member interposed in said train and adapted to shear when the motion of the ram is arrested during one portion of its forward stroke, and said yielding means being adapted to yield when the movement of the ram is arrested during another portion of its forward stroke when the parts are of less angularity and approaching alignment to permit the crank and rod to cross the dead center.

4. In an automatic stoker, the combination of a ram, means for reciprocating said ram comprising a connecting rod having relatively longitudinally movable sections, a crank and a train of gearing for rotating the crank, a frangible member interposed in said train and adapted to shear to relieve the train when said ram is incapable of movement in one position, and yielding means interposed between the sections of said rod adapted to yield to permit relative longitudinal movement of said sections when said ram is incapable of movement in another position.

5. In an automatic stoker, the combination of a ram, means for reciprocating said ram comprising a connecting rod having relatively longitudinally movable telescopic sections, means for limiting the movement of said sections with respect to each other, a crank and a train of gearing for rotating the crank, a frangible member interposed in

said train and adapted to normally maintain said sections in extended position and to yield to permit relative movement of the sections should the ram 10 become jammed at other points in its path. 5 normally maintain said sections in extended position and to yield to permit relative movement of the sections should the ram 10 become jammed at other points in its path. In witness whereof, I have hereunto set my hand this 23rd day of February, 1922.

WILLIAM C. STRIPE.
